UNITED STATES PATENT OFFICE.

STEPHEN P. ENRIGHT AND JOSEPH F. DILLON, OF PHILADELPHIA, PENNSYLVANIA;
SAID DILLON ASSIGNOR TO SAID ENRIGHT.

FLUSH VALVE.

Application filed November 2, 1926. Serial No. 145,767.

Our invention relates to new and useful improvements in flush valves, and has for its primary object to provide a valve of this description which, when seated, will prevent any possibility of outflow or leakage from the water or other liquid supply, but when opened will remain open until the liquid pressure in the tank or other source of supply has been reduced to a predetermined point, when the valve will automatically close and be firmly held against its seat by the remaining pressure within the tank.

A further object of our invention is to so design and construct a valve of this description that it will be especially adapted for use in connection with flush tanks for toilets whereby the passage of water from the tank to the bowl is made more positive and more effective than has heretofore been the case, and to greatly reduce the chance of leakage and to eliminate repairs.

With these and other ends in view, this invention consists in the details of construction and combination of elements hereinafter set forth and then specifically designated by the claims.

In order that those skilled in the art to which this invention appertains, may understand how to make and use the same, we will describe its construction in detail, referring by numerals to the accompanying drawings forming a part of this application, in which:

Fig. 1, is a perspective showing a toilet bowl of ordinary type, and illustrating the manner of coupling the tank of any suitable design to the bowl with our improved flush valve.

Fig. 2, is an elevation on a reduced scale partly broken away and sectioned to illustrate the fact that said tank is air-tight or hermetically sealed with the exception of the water inlet pipe.

Fig. 3, is a horizontal, central longitudinal section of the flush valve and its casing on an enlarged scale relative to Fig. 1, relative to practice normally full size, the actuating stem and the eccentric being left in plan.

Fig. 4, is a section similar to Fig. 3, but taken at right angles thereto showing the valve and the mechanism carried thereby in its locked-open position.

Fig. 5, is a perspective of the valve including the barrel carrying the same.

Fig. 6, is a view similar to Fig. 5 of the insert sleeve in which the barrel operates.

In carrying out my invention as herein embodied, 10 represents a tank, which may be of any shape or size, but so enclosed as to trap and compress air therein by the inflow of water through the supply pipe 11.

12 represents a nipple which is secured in any convenient or well-known manner in the wall of the tank, and this nipple is intended to receive the internally threaded end of the outlet pipe 13, the outer end of said outlet pipe being threaded for the reception of the union nut 14, said nut serving to firmly hold in place against the outer end of the outlet pipe 13, the casing 16. By this arrangement, the casing may be readily put on or removed from the outer pipe without displacing the nipple, and as hereinafter explained serves to give ready access to the working parts of the valve.

Within the casing 16 is fitted a sleeve 17 which has a portion of its wall cut away as indicated at 18 in Fig. 6 for the purpose hereinafter explained, and this casing is intended to receive the barrel 19, the latter being adapted to slide freely back and forth within the casing, and be tilted therein in such manner that the edge 20 of this barrel may be forced downward into the cut-away portion 18 and engage with the edge 21 of the forward semi-ring of said casing. Such an engagement being clearly shown in Fig. 4.

Projecting from the head of the barrel is a threaded rod 22, over which the valve proper 23 is positioned, and this valve 23 is held in place upon the head of the barrel 19 by the weight washers 24, which are in turn held in place by the nut 25, threaded upon the rod 22; the valve 23 is preferably a disc of leather or other slightly compressible material so as to close upon the valve seat 26 in such manner as to prevent leakage at this point.

The valve is prevented from turning upon its axis by means of the guide pin 27, which as here shown is an extension of the screw 28, also holding the sleeve 17 in position, while at the same time permitting the barrel to have both a longitudinal sliding movement and a tilting movement, as will be readily understood.

The inner end of the barrel is provided with a vertical cross bar 29 having its outer surface curved so as to provide the shoulder 30 upon which the eccentric 31 may act to depress the inner end of the barrel for forc-

ing the edge 20 downward into engagement with the edge 21, as before described.

This eccentric 31 is carried by the inner end of the lever shank 32, which is housed in the gland box 33 and the gland nut 34, the latter serving to compress the packing 35 for preventing leakage around the stem, as is customary in such structures; the outer end of the stem carrying the actuating handle 36.

From the foregoing description, the operation of our improved flush valve will be obviously as follows: Water having been admitted to the tank through the supply pipe 11 will compress the trapped air in said tank until the pressure of said air balances the pressure of the inflowing water, and this water under pressure will close and hold the valve 23 firmly against its seat 26, preventing any outflow, but when the actuating handle is operated to revolve the shank 32, the eccentric 31 will force the valve backward from off its seat, and said eccentric acting upon the shank will tilt the inner end of the barrel downward thereby canting the valve, which will permit the water to flow from the tank through the cut-away gap 37 in the under side of the barrel, and from thence through the barrel, the sleeve and the casing to the bowl 38.

As soon as the water is flowing at full volume through the cut-away gap, the valve will be held in its upward tilted position by this water flow, and so long as said valve is thus held the edge 20 engaging with the edge 21 prevents the closing of said valve. This permits the releasing of the actuating handle, and the return of the eccentric to its normal position without effecting the closing of the valve, but when the pressure upon the water within the tank has decreased sufficiently to permit the heft of the weight washers to force the valve and barrel to a normally horizontal position against the then reduced flow of water, the valve will simultaneously close upon its seat under the influence of this reduced water pressure, and be there held until the eccentric is again operated to force the barrel inward and its outer end downward, as already described.

Although water will be flowing into the tank through the supply pipe while the valve is open, the outlet pipe being of much greater capacity than this supply pipe, the tank will be readily emptied to the point where the valve will close, but as soon as the valve is closed, the tank will be again partially filled, and the maximum pressure re-established.

It is to be noted that the use of a valve of this description in connection with a toilet bowl provides for the injection of the flush water to the bowl under pressure, and therefore more thoroughly cleanses the bowl and produces the desired result with less water

than where the ordinary gravity tank is used, and further that as the valve is seated under pressure further than that of the low head of water in the ordinary tank, its seating is more effective; and leakage cannot take place between the valve and its seat.

Also as the working parts are exceedingly simple requiring no accurate fits or adjustments, the wear and tear on such a valve are negligible.

The threaded rod 22 is of sufficient length to provide for the addition of washers, such as the weight washers 24, thus providing for increasing the weight upon the outer end of the barrel to establish the proper relation between this weighting and the pressure in the tank for the closing of the valve at the predetermined point. This adjustment is readily made by uncoupling the union nut 14, removing the casing when free access will be had to the weight washers for adding thereto or taking away from, as will be readily understood.

While we have illustrated our flush valve in use in connection with the toilet bowl and tank, it is obvious that it may be put to various other uses, where it is desirable to hold the head of water against outflow, then permit its outflow and automatically shut off the same at a predetermined point.

If found desirable, a stop bracket 39 may be secured to the casing and so positioned as to limit the revolving of the actuating handle in one direction so as to permit the eccentric from being moved in the reverse direction in order that it may always be moved in the proper direction to first force the valve from off its seat and then tilt the inner end of the valve downward, consequently canting the valve upward when off its seat.

It is to be noted that this style of flush valve provides for the placing of the tank in any convenient location, such as embodying it in the wall, as it is not necessary to have the tank in close proximity to the bowl, since the outlet pipe may be of sufficient length to lead the water from the tank to said bowl.

Of course we do not wish to be limited to the exact details of construction as herein shown as these may be varied within the limits of the appended claims without departing from the spirit of our invention.

Having thus fully described our invention, what we claim as new and useful is:

1. A flush valve comprising a casing, a tilting member fitted to slide within said casing, means for forcing the tilting member rearward and tilting its inner end downward, means for engaging this inner end, a valve seat, a valve carried by the tilting member adapted to close upon said seat, an opening through the under side of the tilting member for causing the outflow of water.

to hold the valve from off its seat until the predetermined water pressure has been reached.

2. In a device of the character described a casing, means for coupling said casing to a tank, a valve seat carried by the casing, a valve adapted to close upon said seat, a tilting member by which the valve is carried, a sectional weight also carried by the tilting member, means for holding the valve from off its seat when the tilting member is tilted and means for tilting said member.

3. In a device of the character described, a casing, means for coupling said casing to a supply tank, a sleeve fitted within said casing, said sleeve having a cut-away portion leaving a ring portion at one end thereof, a barrel fitted to slide and tilt within said sleeve, a valve carried by the barrel and adapted to close upon a seat carried by a casing and an eccentric adapted to force the barrel rearward and tilt its outer end downward so as to engage said outer end with the ring portion of the sleeve, means for preventing the rotation of the barrel and means for varying the weight upon the outer end of the barrel to adjust the functioning of the barrel to the water pressure within the tank.

4. In a device of the character described a casing, a sleeve fitted within said casing, said sleeve having a cut-away portion to form an edge, a barrel fitted to slide and tilt within the casing, means for preventing the rotation of the barrel, means for forcing the barrel rearward and tilting its inner end to bring about engagement with the cut-away portion of the sleeve, a valve carried by the outer end of the barrel, a seat carried by

the casing against which said valve is adapted to close, a rod projecting from the rear end of the barrel, a series of weight washers mounted upon said rod in such manner that they may be increased or decreased and means for coupling the casing to a supply tank.

5. In a flush valve of the character described a casing, a seat carried by said casing, a barrel fitted to slide and tilt within said casing, a valve carried by the barrel, means for increasing or decreasing the weight upon the outer end of the barrel, an actuating spindle projecting into the casing, a stuffing gland surrounding said stem and carrying a gland nut and eccentric for sliding and tilting the valve, said eccentric being carried by the inner end of the stem, an actuating handle carried by the stem and means for limiting the revolving of the stem.

6. In a device of the character described, a casing; a valve seat carried by said casing, a valve adapted to close upon said seat; a tilting member carrying said valve, said tilting member having a water passage-way through its under side to permit water to flow in an upward direction to the interior of the tilting member, whereby when the valve is manually forced off its seat, the flow of water through said passage-way will hold said tilting member in an upward tilted position; and means for preventing the outward movement of the tilting member while in this tilted position.

In testimony whereof, we have hereunto affixed our signatures.

STEPHEN P. ENRIGHT.
JOSEPH F. DILLON.
